UNITED STATES PATENT OFFICE.

WILHALM H. WINTERS, OF PROCTORVILLE, OHIO.

DESIGN FOR AN UPPER FOR BOOTS OR SHOES.

SPECIFICATION forming part of Design No. 31,106, dated June 27, 1899.

Application filed May 25, 1899. Serial No. 718,306. Term of patent 7 years.

To all whom it may concern:

Be it known that I, WILHALM H. WINTERS, a citizen of the United States, residing at Proctorville, in the county of Lawrence and State of Ohio, have invented and produced a new and original Design for the Upper of a Boot or Shoe; and I do hereby declare the following to be a full, clear, and exact description of the same, reference being had to the accompanying drawings, forming a part thereof.

In the accompanying drawings, Figure 1 is a side elevation of the upper or leg portion for a boot embodying my design. Fig. 2 is a perspective view of the same, and Fig. 3 is a transverse section on the line xx of Fig. 1.

The leading feature of my design consists of an upper for a boot or shoe having an extended top or leg portion provided with a vertically-arranged expandable portion and a closed front portion provided with holes for imitation lacing.

1 in the drawings represents the upper, which is formed with a top or leg extension

2, the latter being flaring or bell-shaped, and said upper is formed with a vertically-arranged expandable portion 3 and is open at top and closed at front by a portion 4. The said upper or leg portion is also provided at the front with extending portions 5, which latter are provided with eyelets 6 for imitation lacing. The inner face of the expandable portion is covered with a lining 7. The upper or leg portion is also formed with the usual vamp portion 8 and the quarter or heel portion 9.

Having now described my invention, what I claim as new, and desire to secure by Letters Patent, is—

The design for an upper for a boot or shoe, substantially as herein shown and described.

In testimony whereof I hereunto affix my signature in presence of two witnesses.

WILHALM H. WINTERS.
